UNITED STATES PATENT OFFICE.

SAMUEL WARREN POTTS, OF NEW YORK, N. Y., ASSIGNOR TO THE BRISTOL COMPANY,
OF WATERBURY, CONNECTICUT, A CORPORATION OF CONNECTICUT.

SETBACK-COUNTER.

1,015,710.

Specification of Letters Patent. Patented Jan. 23, 1912.

Application filed November 22, 1910, Serial No. 593,596. Renewed November 13, 1911. Serial No. 660,162.

To all whom it may concern:

Be it known that I, SAMUEL WARREN POTTS, a citizen of the United States, residing in the city of New York, borough of Manhattan, county and State of New York, have invented certain new and useful Improvements in Setback-Counters, of which the following is a full, clear, and exact specification.

This invention relates to setback counters and has for an object to provide an improved counter wherein a resetting train is continuously in operative position relative to the counter dials and in position to pick up each of the several dials at the proper time upon its actuation for the bringing of the dials to zero simultaneously.

In the drawings accompanying and forming a part of this specification, one practicable embodiment of a form of my invention is illustrated, wherein—

Figure 1 is a front elevation of the device, the top plate being removed. Fig. 2 is a longitudinal section of the casing showing the mechanism in elevation, this being taken on a plane at about right angles to that illustrated in Fig. 1. Fig. 3 is a longitudinal section of one of the counter units; and Fig. 4 is a partial elevation and a partial section showing the by-pass relation between the means for connecting the resetting pinion with the dial.

In the mechanism illustrated, the supporting framework is in the nature of a casing having a base-plate 5, with boxlike sides 6, and a top-plate 7. The top-plate will, of course, in the mechanism herein illustrated, be provided in the well known manner with openings through which the figures of the dial will be read. There are shown four counter units in the present illustration, each of which units embodies a counter-disk 8, provided with a series of numerals. Each of the disks is shown fast with a hub 9, and a pallet-wheel 10, having as many points as there are numerals upon the dial. The hub member is mounted upon a shaft 11, having bearings in the top and bottom plates 7 and 5 respectively. In the present showing, for the purpose of permitting the dials to overlap for the conservation of space, the shafts are shown arranged obliquely to the base-plate 5. The first unit has fast with the dial a ratchet-wheel 12, for the engagement of a pawl 13,

pivoted upon an actuator-lever 14, which will be connected to the movable part of the mechanism, the movements whereof are to be counted by the instrument. A spring 15 is shown engaging the pawl for permitting and assisting in its proper work. A coil-spring 16 is illustrated for holding the actuating-lever 14 in its upward or full-line position of Fig. 1. The various units, with the exception of the last of the series, has associated with its pallet-wheel 10, a pin 17, for engaging the pallet-wheel of the next unit for advancing this the distance of one step upon each rotation, so that each unit will be advanced one step at each rotation of each preceding unit of the series in the well known manner.

Suitable springs, designated without preference by the reference character 18, are provided for engaging the pallet-wheels and holding these against accidental movement. The springs also assist in centering the numeral as the disk or dial is moved into position. The last unit is shown provided with a spring-finger in the nature of a pawl 19, which will prevent reverse movement of this particular unit. A particular reason for preventing reverse movement of this unit is that in the present illustration this is the one with which the resetting actuator is associated.

The shaft 11 of the last unit in the series is shown extended out through the top-plate 7, and provided with a wing member 20. This shaft also has fast upon it a pinion 21, which constitutes one member of the resetting train, the resetting train being shown as embodying a series of pinions 21, continuously in mesh one with the other and continuously in operative position relative to the units. Each of the dials has fast with it a member for engaging an abutment associated with that particular member of the resetting train which is connected with that unit. In the present showing each of the pallet-wheels 10, carries a spring-finger 22, located in position for being engaged by a pin 23, carried by the pinion 21, upon the forward resetting movement of the pinion in such manner that the dial of that unit will be moved forward. The connection between the spring-finger 22, and the pin 23, is of a by-pass nature, so that as the dial is advanced normally in the counting operation of the device the spring will ride over

the pin 23, but upon the movement of the pinion in a normal direction of forward rotation of the dial, the spring and the pin will come together and drive forward the dial. The pins 23, and the springs 22, on the respective pinions and dials, are located in such positions relative to each other and also in each unit relative to all those in the series, that in the forward advance of the 10 resetting train the dials will be picked up and brought into position so that the same numeral on each will appear at the reading line, and the further advance of the resetting train will bring all the dials to such a 15 position that the zero character will be presented at the reading line in each unit, and the zero characters upon all of the units will come to the reading line simultaneously.

Although but one form of carrying out 20 my invention has been illustrated, yet it will be apparent that many changes may be made without departing from the scope of my invention.

Having thus described my invention, 25 what I claim and desire to secure by Letters Patent is:

In a resetting counter, the combination

with a base-plate, of a series of rotary counter units each unit comprising a spindle set obliquely to the base-plate, a counter dial, a pallet wheel fast with the counter dial and mounted on the spindle, a spur gear mounted on the spindle free of the counter dial and pallet wheel, a pin carried by the spur gear and projecting toward the 30 pallet wheel, and a spring finger carried by the pallet wheel and projecting toward the spur gear and rearwardly of the direction of rotation of the pallet wheel, the counter dial and pallet wheel of each successive unit 35 overlapping those of the preceding unit, an actuator finger carried by the upper face of each overlapping pallet wheel for engaging and actuating the next succeeding pallet wheel, and means for driving the resetting 40 train.

In witness whereof I have hereunto set my hand in the presence of two subscribing witnesses.

SAMUEL WARREN POTTS.
